(57) **CLAIM**

The ornamental design for a display table, as shown and described.

DESCRIPTION

FIG. 1 is a front perspective view of the display table design. FIG. 2 is a front elevation view of the display table design. FIG. 3 is a rear elevation view of the display table design. FIG. 4 is a right side view of the display table design. FIG. 5 is a left side view of the display table design. FIG. 6 is a top view of the display table design. FIG. 7 is a bottom view of the display table design; and, FIG. 8 is a bottom perspective view of the display table design.

The broken lines in the figures are for the purposes of illustrating portions of the display table that form no part of the claimed design.
